FLUID STRIPPER FOR PUMP PISTONS

Original Filed Nov. 17, 1938

UNITED STATES PATENT OFFICE

2,340,471

FLUID STRIPPER FOR PUMP PISTONS

Charles K. Huthsing, Grosse Pointe, Mich.

Original application November 17, 1938, Serial No. 240,892, now Patent No. 2,256,902, dated September 23, 1941. Divided and this application August 2, 1941, Serial No. 405,138

2 Claims. (Cl. 236—28)

This invention relates to a fire extinguisher of the hand type and is a division and continuation in part of applicant's co-pending United States applications, Serial No. 240,892 and Serial No. 350,681, filed November 17, 1938, and August 3, 1940, respectively, now matured as Patents No. 2,256,902 and No. 2,326,861, issued September 23, 1941, and August 17, 1943, respectively.

The main objects of this invention are to provide a fire extinguisher which is assured of being in operable condition regardless of the length of time of non-use and which, therefore, can be depended upon at all times in the event of emergency; to provide improved means for stripping the fluid from the piston rod so as to prevent slight leakage or dripping when the rod is reciprocated through its packing gaskets and which means is resilient and yielding so as to not become frozen on the rod by corrosion during long periods of non-use.

An illustrative embodiment of this invention is shown in the accompanying drawing, in which:

Fig. 1 is an enlarged, fragmentary, medial sectional view of the improved fire extinguisher showing the details of construction of the piston rod packing glands and sealing means;

Fig. 2 is a sectional view taken on the line 2—2 of Fig. 1; and

Fig. 3 is an enlarged, fragmentary side elevation of the axially slidable sleeve as viewed from the line 3—3 of Fig. 1, showing a portion of the cylindrical sleeve of the lower extension of the handle and showing a portion of the cap and flange portions thereof in broken lines.

The important problem of the fire extinguisher manufacturer is to make an apparatus which is leak-proof when the extinguisher is not in use and at the same time have an extinguisher which unquestionably will operate immediately when an emergency of fire arises. It is, of course, self-evident that a fire extinguisher from which the fire extinguishing fluid has leaked or evaporated out or a fire extinguisher in which the working parts are frozen and will not operate in case of an emergency are both worse than having no fire extinguisher at all.

A problem encountered in the use of fire extinguishers having felt packing glands for the piston rod has been that of the fluid adhering to the piston rod as it is drawn through the gaskets and then dripping off in the hands of the user during the pumping strokes.

In the present invention, this objection has been overcome by having the helical compression spring, which compresses the rod gaskets, fit

tightly around the rod, so that it acts as a resilient gripping fluid stripper. Due to the yieldability of the spring, it may have a snug fit around the rod, but will not freeze thereto by corrosion.

In the construction shown in the drawing, a cylindrical reservoir 5 has the usual pumping and valve mechanisms contained therein.

The upper end of the reservoir is closed by a cap 9 brazed or otherwise sealed thereto in which is a filler opening with screw closure plug, not shown, in the usual manner of fire extinguishers of this character. The cap 9 has an annular collar or sleeve portion 11, extending axially outwardly and having an axial opening therethrough, and a cylindrical skirt portion 12 which extends axially inwardly from the cap. The opening through the sleeve 11 has an easy working fit with a piston rod 14 which is slidable therethrough. The outer axial face of the sleeve 11 forms a sealing face 13 which coacts with an annular ring gasket 15 carried by an annular sealing member 16 which is rigidly brazed or otherwise secured to the piston rod 14. The member 16 comprises an axially extending cylindrical skirt portion 17 which embraces and carries the gasket 15, and an oppositely extending cylindrical sleeve portion 18, the axial end of which terminates in an exteriorly threaded end 19. A handle 20, having an axially extending hollow shank 21, is threaded on the end 19 in abutting relationship against a shoulder of the sleeve 18, to limit and position the parts.

An axially slidable sleeve 22 surrounds the annular sealing member 16 and piston rod 14 in spaced relation thereto and the upper end is provided with a radially disposed, inwardly extending flange 23 which is freely slidable on the sleeve portion 18 of the annular sealing member 16. A helical compression spring 24 is provided in the space between the fixed sleeve 18 and the slidable sleeve 22 and bears between the sealing member 16 and the flange 23 of the sleeve 22.

The lower end of the slidable sleeve 22 is provided with diametrically opposed radially extending lugs 25 and 26, each having two cam surfaces on their outer axial faces. The two cam surfaces on each lug have reverse slopes forming high points at the center of each lug as shown at 100 in Figure 3. The outer axial faces of these lugs engage the flange portions 27 and 28 integrally formed on the cap 9, said high points 100 of these faces, entering the openings 101 and 102. Said openings 101 and 102 are preferably shaped to provide relatively sharp corners which engage

the cam surfaces of the lugs 25 and 26 as shown at 103 and 104 in Fig. 3, thus providing a substantially line-to-line contact. The lugs are depressed axially while in the position shown in Fig. 2 at 105 and 106 and then rotated in either direction to the position described above. This construction eliminates the possibility of corrosion and freezing which exists where an area-to-area contact is employed.

The lower end of the hollow shank 21 is flared out to provide a cylindrical sleeve 31 which surrounds the axially slidable sleeve 22 and which is provided with diametrically opposed axially extending inwardly presenting slots 32 and 33 which receive similarly disposed ribs 34 and 35, respectively, which are integrally formed on the slidable sleeve 22 whereby the sleeve and handle are non-rotatably secured while permitting relative axial movement therebetween.

The hollow shank 21 of the handle 20 is provided with an axially extending bore 36 in which is housed a helical compression spring 37, one end of which abuts the blind end of the bore 36 and the other end of which contacts an axially slidable floating seal 38, the inner face of which fits upon and closes one end of a discharge tube 40 when the handle is in closed position, as shown in Fig. 1.

The inner end of the sleeve 12 is interiorly threaded to receive the exteriorly threaded axially extending sleeve portion 41 of a fitting 42 which is provided with an oppositely extending cylindrical sleeve portion 43 which has a free sliding fit on the piston rod 14. The space between the piston rod 14 and the sleeves 12 and 41 is provided at its upper end with a felt gasket 44, a cork washer 45, and a brass washer 46 bearing thereagainst. The gasket 44 is constantly urged in compression around the piston rod 14 by a helical compression spring 46, which snugly surrounds and yieldingly grips the rod 14, so as to strip the fire extinguishing fluid from the rod during reciprocation thereof. One end of the compression spring 46 bears against the washer 45 and the other end thereof bears against a similar but smaller washer 47 which fits against a felt gasket ring 48 disposed at the other end of the space, thus providing a double yielding seal around the piston rod which is automatically tensioned at all times and which prevents substantial leakage of fluid around the piston rod during its reciprocation when subjected to pumping action.

The piston rod 14 is surrounded by a pumping cylinder 49, one end of which is fixed to a rotatable head 50 and the other end of which is similarly fixed in a similar rotatable head (not shown).

The head 50 which supports the upper end of the pumping cylinder 49 is provided with a felt packing ring or gasket 64 which is retained by a relatively thin brass washer 65 secured on an annular radially extending seat by rolling over the metal at the edge of the opening which receives the washer, as shown at 66. The inner edge of the washer 65 rides upon the outer surface of the axially extending sleeve portion 43 which serves as a bearing for supporting the upper end of the suction mechanism and which bearing, having relatively small metal to metal contact, will have a minimum of tendency to stick and present very little friction to rotation of the head, thus providing a structure which will have freedom from freezing by reason of corrosion or the like.

The head 50 is provided with a laterally extending weighted arm having passageways therethrough with ball check valves which serve as suction ports for the pumping cylinder. The upper end of the cylinder 49 communicates with a radially extending port 67 controlled by ball valve 68 which leads to an axially extending passageway 69, one end of which is controlled by a ball check valve 70 and which in turn communicates with a second radially extending port 71, the outer open end of which lies closely adjacent to the inner peripheral wall of the reservoir 5. The end of the passageway 69 opposite to the ball check valve 70 communicates with an axially extending tube 72, the upper end of which is rigidly secured in axial alignment therewith. A detailed description and illustration of the complete mechanism is shown in my above-identified patents.

20 A metal rod 76 is housed within the tube 72 and functions to tap the ball check valve 70 off of its seat when the fire extinguisher is inclined upwardly, thus insuring free communication for the passage of fluid from the reservoir into the tube 72 and head 50.

25 In the operation of this fire extinguisher, the reservoir 5 is filled with fire extinguishing fluid through an opening in the head 9 (not shown) in the usual manner. During non-use of the fire extinguisher the cam lugs 25 and 26 are engaged 30 under the inturned flanges 27 and 28, thus compressing the helical spring 24 between the radially extending inturned flange 23 and the annular sealing member 16 which is brazed to the 35 piston rod 14, thus compressing the gasket 15 between the sealing member 16 and the outer axial face 13 of the sleeve 11. Thus a fluid tight effective seal is maintained at all times which will prevent leakage or evaporation of the fluid 40 within the reservoir past or through the opening in the sleeve 11 around the piston rod 14.

45 When the handle is in the foregoing described closed and sealed position, the lower face 39 of the floating seal 38 is tightly pressed against the upper end of discharge tube 40 by the helical compression spring 37, thus preventing any leakage or evaporation of fluid through the discharge tube 40 and nozzle opening 8 of the apparatus.

50 When it is desired to operate the fire extinguisher, the reservoir portion 5 is grasped in one hand, the handle 20 in the other, and the handle rotated relatively to the reservoir, in either direction, until the cam lugs 25 and 26 spring from under the flange portions 27 and 28, at which 55 time the handle is free to move axially.

During the upward stroke of the piston, the fluid which is in the pumping cylinder 49 is prevented from passing out around the piston rod 14 through the head 50 by reason of the stripping action of the spring 46 and the resilient felt packing rings 44, 48 and 64.

55 It will also be equally evident that when the handle 20 is forced downwardly so as to compress the spring 37, the floating seal 38 will effectively close the upper end of the discharge tube 40 and prevent evaporation or leakage of the fluid thereinto. When the cam lugs 25 and 26 are rotated underneath the flanges 27 and 28, the sliding sleeve 22 will move axially downwardly toward the head 9, as shown in Fig. 1 of the drawing, thus compressing the spring 24 which yieldingly holds the annular sealing member 16 and gasket 15 tightly upon the sealing face 13 of the sleeve member 11.

75 The cylindrical sleeve portion 12 is provided

with a plurality of axially extending slots or notches 90 through which the fluid that is stripped from the piston rod 14 may return to the interior of the reservoir.

What is claimed is:

1. In a piston rod packing, a compressible, annular packing adapted to surround and snugly fit the rod and a helical spring having spaced convolutions with a normal interior diameter slightly less than the exterior diameter of the rod and adapted and arranged to yieldingly embrace the rod for stripping fluid therefrom during reciprocation thereof, said spring having free ends and exerting a yielding axial pressure on

said packing for compressing said packing around the rod.

2. In a piston rod packing, a pair of axially spaced compressible, annular packings adapted to surround and snugly fit the rod and a helical spring having spaced convolutions with a normal interior diameter slightly less than the exterior diameter of the rod and adapted and arranged to yieldingly embrace the rod for stripping fluid therefrom during reciprocation thereof, said spring having free ends and exerting a yielding axial pressure on said packings for compressing said packings around the rod.

CHARLES K. HUTHSING.
